2 Sheets-Sheet 1

A diagram of a simple rectangular labyrinth. It consists of a large outer rectangle with a smaller inner rectangle inside. The two rectangles are connected at their top and bottom edges. There are four vertical walls on the outer rectangle, and the central opening is a horizontal slot between the two rectangles.

UNITED STATES PATENT OFFICE.

GEORGE DALIANIS, OF NEW YORK, N. Y.

LOCK.

Application filed September 14, 1923. Serial No. 588,922.

To all whom it may concern:

Be it known that I, GEORGE DALIANIS, a citizen of the United States, residing at New York, in the county of New York and State of New York, have invented certain new and useful Improvements in Locks; and I do declare the following to be a full, clear, and exact description of the invention, such as will enable others skilled in the art to which it appertains to make and use the same.

My invention relates to improvements in house and apartment door locks and more particularly to those of the type having a locking bolt which is tripped by inward movement of the usual beveled latch, incident to closing the door, whereby said locking bolt is projected to co-act with the latch in doubly locking the door.

One object of my invention is to provide a lock of the character set forth provided with means for locking the bolt against projection every time the door is closed, for instance during the day time, this means, however, being movable to an inoperative position so that whenever it is desired to have the bolt project automatically with closing of the door, this can be done.

A further object is to provide improved means for tripping the bolt holding tumbler when the door is closed, permitting a spring to come into play to project the bolt.

Yet another object is to provide a novel arrangement of parts whereby both the locking bolt and the latch may be simultaneously retracted by means of a key, the bolt being held in retracted position while the latch is released to be again projected under the influence of its spring.

With the foregoing in view, the invention resides in the novel subject matter herein-after described and claimed, the description being supplemented by the accompanying drawings.

Figure 1 is an elevation, partly in section, showing a lock constructed in accordance with my invention, the bolt and the latch being shown in locked position.

Figure 2 is a view similar to Fig. 1, showing the locking bolt and the latch partially withdrawn.

Figures 3 and 4 are detail perspective views showing the additions which I have

made to a well known lock structure, to carry out my invention.

In the drawings above briefly described, the numeral 1 designates a suitable lock casing containing a spring pressed beveled latch 2 and a locking bolt 3 provided with a projecting spring 4. A spring-applied tumbler 5 is pivoted at 6 to the locking bolt 3 and is cooperable with a post 7 in the casing to hold the bolt in either projected or retracted position. The numeral 8 merely designates a well known rocker controlled by a finger piece from the inside of the door, for releasing the tumbler 5 and retracting the locking bolt 3 when desired, without the necessity of using a key. When it is desired to hold this bolt in retracted position, regardless of release of its tumbler 5 by means yet to be described, this may be done by means of a pin 9 passing slidably through a slot 10 in the casing and capable of being moved into engagement with a shoulder 11 on the bolt 3, when the latter is fully retracted.

For retracting the lock 3 by hand, and releasing its tumbler 5, an ordinary cylinder type of locking mechanism is provided within an opening 12 in the casing, this mechanism however being omitted for sake of clearness.

The numeral 13 designates a lever which may well be fulcrumed upon the post 7, the lower end of said lever having a pin 14 and slot or other suitable sliding connection 14 with the latch 2, while the upper end of said lever is provided with a shoulder 15 engaged by a nose 15' on a cam 16 located behind the bolt 3 and pivotally mounted on a suitable stud or the like 17. A cam actuator 18, preferably in the form of a horizontal lever, is fulcrumed at 19 to the bolt 3 and as here shown, is provided with a lateral lug 20 cooperable with the curved edge 21 of the cam 16, for the purpose of rocking said cam about its pivot 17, as the actuator 18 is forced inwardly by inward movement of the bolt 3, under the influence of the key operated mechanism. The end of the actuator 18, remote from its pivot 19, is connected by means of a link 22 or other suitable means, to the tumbler 5. Since the actuator is tied to the

tumbler 5, it cannot have vertical movement independent of the tumbler and therefore the actuator will be held against upward swinging when the bolt 3 moves inwardly and consequently causes the lug 20 to tilt the cam 16 downwardly and furthermore, when the bolt is fully retracted and the tumbler 5 again rises to an operative position to hold said bolt retracted, the tumbler pushes upwardly upon the link 22 and thus swings the actuator 18 upwardly, thereby releasing the pressure of the lug 20 upon the cam 16 and permitting the latch 2 to again project under the influence of its spring. This spring, a portion of which is designated by the reference character 23, may well act upon the lever 13.

While any desired connections may be employed between the link 22 and the parts 5 and 18, I prefer to establish these connections by means of loosely interfitting notches in the several parts as shown more particularly at 24 in Fig. 3.

From the construction so far described, it will be seen that when the bolt 3 is moved inwardly by key operated mechanism (not shown) the lug 20 and the actuator 18 tilt the cam 16, thereby rocking lever 13 and retracting the latch 2, so that the door can be opened. As soon as the key operated mechanism however permits the tumbler 5 to come into play to hold the bolt 3 retracted, the link 22 moves the actuator 18 upwardly, releasing the pressure of lug 20 on cam 16 and permitting the latch 2 to again project, while the bolt 3 remains retracted. Now, if it is desired that the bolt 3 shall not be projected the next time the door is closed, the pin 9 is moved into engagement with the shoulder 11. Otherwise, closing of the door and inward movement of the latch 2, incident to this closing, will cause projection of the bolt 3 under the influence of its spring 4, due to the fact that I provide a pin or other projection 25 on the lever 13 for contacting with and releasing the tumbler 5 when the latch 2 is moved inwardly.

Assuming that the bolt 3 is held in retracted position by the tumbler 5, that the pin 9 is not engaged with the shoulder 11, and that the door is in open position, it will be seen that closing of this door will cause the latch 2 to move into the casing, thus rocking the lever 13 and causing pin 25 to release the tumbler 5, whereupon the spring 4 comes into play to automatically project the bolt 3 for cooperation with the latch 2 in doubly locking the door.

As excellent results may be obtained from the details disclosed, they are preferably followed, but it is to be understood that within the scope of the invention as claimed, numerous minor changes may be made.

For instance, although I have used well

known lock parts and have merely added the link 22 and the pins 9 and 25, it will be understood that if desired, the invention can be carried out in other ways. It may be further stated that all parts shown below the broken line A, are well known, for the purpose of controlling the latch 2 by hand from the usual knob shaft.

I claim:

1. A lock comprising a casing containing a spring-pressed latch, a lock-controlled bolt and a lock-controlled tumbler for said bolt; a movable member mounted in said casing and operatively associated with said latch for withdrawing the same, an actuator for said movable member mounted movably on said bolt and operative to effect withdrawal of said latch automatically when the bolt is withdrawn, and a connection between said actuator and said tumbler for automatically moving said actuator out of operative relation with said movable member when said tumbler returns to operative position with the bolt retracted.

2. A lock comprising a casing containing a spring-pressed latch, a lock-controlled bolt and a lock-controlled tumbler for said bolt; a movable member mounted in said casing and operatively associated with said latch for withdrawing the same, an actuator for said movable member mounted movably on said bolt and operative to effect withdrawal of said latch automatically when the bolt is withdrawn, and a link connecting said actuator with said tumbler for automatically moving said actuator out of operative relation with said movable member when said tumbler returns to operative position with the bolt retracted.

3. A structure as specified in claim 2; the connections of said link with said tumbler and actuator being effected by providing said link, tumbler and actuator with loosely interfitting notches.

4. A door lock comprising a casing containing a spring pressed beveled latch, a spring-projected locking bolt and a tumbler for normally holding said bolt retracted; means in the casing, for automatically retracting the latch when the bolt is retracted, including a movable member adjacent said tumbler, and a projection on said member operative to release said tumbler and thereby effect projection of the bolt automatically when the latch is forced inwardly by closing the door.

5. A door lock comprising a casing containing a spring pressed latch, a beveled, spring-pressed lock-controlled bolt and a lock-controlled tumbler for said bolt; a lever fulcrumed in the casing and extending transversely of the bolt, said lever being connected with said latch, a movable member mounted in the casing and acting on said lever for retracting the latch, an actuator

for said movable member mounted movably on the bolt and active to effect retraction of the latch when the bolt is retracted, means for automatically disengaging said actuator from said movable member when the bolt is retracted and the tumbler moves to operative position, whereby to permit projection of the latch, and a projection on said lever adapted to strike and release said tumbler when the latch is forced into the casing by closing of the door.

In testimony whereof I have hereunto affixed my signature.

GEORGE DALIANIS.
